STICK FILES

Clarence B. Fowler, Philadelphia, Pa.

Application April 9, 1954, Serial No. 422,132

1 Claim. (Cl. 129—21)

This invention relates to filing devices variously known as stick files, bill files or spindle files, for filing papers on a vertical spike mounted on a movable base. Such unimproved stick files are hazardous because of the exposed spike. Certain more elaborate stick files, having a shield over the point, adversely limit the area on the paper being filed in which a hole can be punched and require excessive concentration, because of the supporting pedestal for the shield.

An object of the invention is to provide a stick file with a safety guard for the point not requiring supporting means limiting the area of perforation of paper to be filed or interfering with casual filing.

Another object is to provide a stick file resembling unguarded stick files in appearance but having the upper end normally terminating in a blunt tube end, with means of temporarily changing, when desired, the end to a spike point.

Referring to the drawing, wherein like reference characters designate like or corresponding parts throughout the several views:

Fig. 1 is a side elevation of the stick file resting upon the top of a desk or table shown cut away.

Fig. 2 is a top plan view.

Fig. 3 is a side elevation showing a sheet of paper tilting the device while being filed thereon. The top of the desk or table is shown cut away.

The spike 4, preferably of steel, is rigidly affixed to the top center of metal base 1 by flat nuts 5 and 6. A thin-walled tube 8, preferably of brass, slidably covers the upper walls of spike 4, extending upward beyond spike point 7. The lower end of tubular sleeve 8 is

2

encircled by offset plate 9, which is affixed to the outside end of 8. The extension of 9 slidably extends downward through slot 10 which penetrates open-bottom base block 1. The end of plate 9 is bent over at 11 so as to limit the upward slide of sleeve 8.

In Figs. 1 and 3 the stick file is shown upon cut away desk or table 12.

In Fig. 3 sheet of paper 13 is shown in process of being filed. This sheet had been lightly pressed obliquely downward against the upper end of tubular sleeve 4, slightly tilting base 1 and sliding both the sleeve and offset plate 9 downward against nut 5, thereby exposing previously hidden point 7, which pierces the paper. Sleeve 8 slightly enlarges the hole made by point 7.

When the paper being filed is released, the stick file returns to horizontal or normal on the desk top, sleeve 8 sliding upward and again covering point 7, due to the weight of base 1.

Plate 9 also prevents filed papers catching under sleeve 8. In Fig. 3 the base 1 is shown tilted on a particular edge. Any of the four lower edges of the rectangle, however, may be used. The base may, if desired, be fashioned into any other tiltable design.

The method of attaching spike 4 to base 1 is optional. Other well-known methods may be used instead of that illustrated.

I claim:

A stick file comprising a hollow base adapted for mounting upon a substantially horizontal surface, an upright spike rigidly affixed to said base, a spike-encasing tube shorter than said spike and normally surrounding the point end but freely movable so that said point may project beyond said tube, and an offset extension member rigidly affixed to the periphery of said tube and projecting downward through an aperture in said base wherein its end is bent over wider than said aperture so as to limit said extension's upward movement, said end being adapted for normal contact with said horizontal mounting surface but moveable below said base when tilted and said tube moved downward.
